(57) **CLAIM**

The ornamental design for an earpiece charger, as shown and described.

DESCRIPTION

FIG. 1 is a front view of the new design for an earpiece charger, the design showing the earpiece charger in a closed configuration;

FIG. 2 is a rear view thereof, in the closed configuration;

FIG. 3 is a bottom view thereof, in the closed configuration;

FIG. 4 is a top view thereof, in the closed configuration;

FIG. 5 is a left side view thereof, in the closed configuration;

FIG. 6 is a right side view thereof, in the closed configuration;

FIG. 7 is a perspective view thereof, in the closed configuration;

FIG. 8 is a front view thereof, in an open configuration;

FIG. 9 is a rear view thereof, in the open configuration;

FIG. 10 is a top view thereof, in the open configuration;

FIG. 11 is a bottom view thereof, in the open configuration;

FIG. 12 is a right side view thereof, in the open configuration;

FIG. 13 is a left side view thereof, in the open configuration;

FIG. 14 is a first perspective view thereof, in the open configuration; and,

FIG. 15 is a second perspective view thereof, in the open configuration.
